UNITED STATES PATENT OFFICE

WILBUR F. HURLBURT, OF EAST ORANGE, NEW JERSEY, ASSIGNOR TO AUTOMATIC SWITCH COMPANY, OF NEW YORK, N. Y., A CORPORATION OF NEW YORK

MAGNETIC SWITCH

Application filed June 27, 1929. Serial No. 374,044.

This invention relates to electric switches which are magnetically controlled and more particularly to switches in which the operating magnet is excited only during the period of closing or of opening the switch.

It is one of the objects of the invention to provide a switch of the foregoing character which shall be simple and compact and which shall comprise a unitary magnetic operating unit and also a unitary switch structure, the latter being either single pole or multiple pole and either single or double throw, the magnetic operating unit and the switch unit each being constructed to be readily interchangeable with other units.

A further object of the invention is to provide a spring pressed electrical contact and positive connections for moving said spring pressed contact into and out of electrical contact by the magnetic operating unit in such a manner that the force is automatically increased as the contact is moved further in against the increasing action of the spring and so that the effective tendency of the spring contact to move out of contact is minimized. This arrangement also insures positive operation of the switch although there may be only a momentary energization of the operating magnet.

These and other objects of the invention will appear to those skilled in the art to which it appertains by a consideration of the following description of one embodiment of the invention taken in connection with the accompanying drawings in which

Fig. 1 is a front elevation of a three-pole double-throw magnetic switch, certain of the electrical connections being shown in diagrammatic form;

Fig. 2 is an end elevation of the operating magnet of Fig. 1;

Fig. 3 is a vertical section taken on the line 3—3 of Fig. 1;

Fig. 4 is a vertical section taken on the line 4—4 of Fig. 1; and

Fig. 5 is a section similar to Fig. 4 with the operating parts in a different position.

Referring to the drawings more in detail the reference character 11 indicates a supporting panel preferably of insulating material

such as slate upon which are mounted bearing brackets 12 and 13 in which is mounted for oscillatory movement a shaft 14 having its axis horizontal and parallel to the plane of the panel. While this shaft is circular in cross section where it passes through the bearings it is preferably square throughout its intermediate portion as indicated at 15 in order that the contact arms may be securely held thereon and prevented from rotating with respect to the shaft. Upper contact arms 16, 17 and 18 are secured to the shaft 14 and lower contact arms 19, 20 and 21 are also secured thereto, there being insulating material 22 interposed between the shaft 14 and the contact arms. Each arm carries a pair of spring pressed contact fingers 23 adapted to make contact with the contact members 24, 25 and 26 respectively when the upper contacts are closed and with the contact members 27, 28 and 29 respectively when the lower contacts are closed.

The upper contact members 24, 25 and 26 may be connected to an emergency line as indicated diagrammatically by conductors 30, 31 and 32. In a similar manner the lower contact members 27, 28 and 29 may be connected as indicated diagrammatically by conductors 33, 34 and 35 to a predominating line. The predominating line is one which normally predominates over the emergency line and maintains connections between such predominating line and the load but when the predominating line is cut off or fails for any reason the emergency line is automatically connected to the load.

Corresponding opposite contact arms have their contact fingers 23 connected by means of flexible cables 36 to central terminal blocks 37, there being a separate block for each of the three poles of the switch. These terminal blocks 37 are connected by means of conductors, shown diagrammatically at 38, 39 and 40, to some suitable load as indicated at 41. As will be clearly seen from Fig. 3 the oscillation of the shaft 14 and the contact arms therewith serves to make contact on the lower contact members and to break contact with the upper contact members when the shaft is oscillated to one extreme position and

when the shaft is oscillated to the other extreme position contact will be made at the upper contact members and contact will be broken at the lower contact members. The 5 oscillation of the shaft 14 is accomplished by means of a forked lever 42 secured thereto. The forked lever 42 is operatively connected with a magnetic operating unit to be presently described.

- 10 The magnetic operating unit has a base or support 43 mounted on the panel 11 and this base carries a solenoid 44 within which is positioned for vertical movement a core 45. The upper portion 46 of the core may be 15 smaller than the main portion of the core and passes through an aperture of corresponding diameter in the support 43. The upper portion 46 of the core is shown threaded and is provided with nuts 47 for adjustably limiting the downward movement of the core 45. The lower portion of the support 43 extends beneath the core 45 to provide bearings for a horizontal shaft 48 disposed parallel to the plane of the panel 11. 20 A momentum member 49, contact disks 50 and 51, and an eccentric 52 may be secured to the shaft 48 to oscillate therewith or they may be secured together so as to oscillate together upon the shaft 48 while the latter 25 remains stationary. A connecting link or pitman 53 has one end pivoted at 54 to the lower end of the core 45, and the other end of the pitman is pivoted at 55 to the momentum member 49. A spring pressed contact finger 56 adapted to make contact with the periphery of the disk 50 is mounted on a member 58 of insulating material and a similar spring pressed contact finger 57 is also mounted on the member 58 and is adapted to 30 make contact with the periphery of the disk 51. The contact disks are so formed that the fingers do not make contact therewith at all times. The contact finger 56 does not make contact with the disk 50 in the extreme position of the shaft 48 shown in Fig. 1 while the contact finger 57 does make contact with the disk 51 in this position. Figs. 2 and 4 show similar position. In Fig. 5 the contact finger 56 is shown as making contact 35 with the disk 50 while the contact finger 57 does not make contact with the disk 51. The conformation given to the contact disks 50 and 51 is preferably such that contact is made in each respective position while the momentum member 49 is swinging from its extreme position to nearly the dead center position but the contact is preferably broken before the momentum member reaches the dead center position. 40 For the operation of the embodiment of the invention shown in the drawings there is also preferably provided a relay having a coil 59 and an armature 60 with two contacts 61 and 62 co-operating with stationary contacts 63 and 64 respectively. When the

coil 59 is excited the armature 60 is pulled up into the position shown in Fig. 1 and connection is made between the contacts 61 and 63. When the coil is de-energized the armature drops into the lower position breaking contact at 61-63 and making connection between the contacts 62 and 64. 70

The electrical connections for the magnetic operating unit and the relay are as follows. One terminal of the coil 59 is connected by 75 means of a conductor 65 to the terminal of the switch supplied by the line conductor 33 and the other terminal of the coil 59 is connected by means of a conductor 66 to the terminal of the switch supplied by the line conductor 34. The armature 60 of the relay is connected by means of a flexible cable 67 and a conductor 68 to the terminal of the switch which is supplied by the line conductor 32. The stationary contact 63 is connected by a conductor 69 to the contact finger 56 while the stationary contact 64 is connected by means of a conductor 70 to the contact finger 57. One terminal 71 of the solenoid 44 is connected by means of a conductor 72 to the shaft 48 and thereby makes contact with each of the contact disks 50 and 51. The connection of the conductor 72 to the shaft is indicated diagrammatically there being various structural details by which this may be 90 accomplished. The other terminal 73 of the solenoid 44 is connected by means of a conductor 74 to the terminal of the switch which is supplied by the line conductor 30. 95

The switch shown in the drawings is particularly adapted for use in hospitals, theatres and similar places where there is a circuit for supplying electricity under normal conditions and also an emergency circuit from a storage battery or other suitable source 100 which emergency line is automatically connected to the load in case of failure of the usual supply for any reason whatever. The complete arrangement for such a purpose 105 will be described in connection with the operation of the switch in order that one ultimate purpose of the switch may be understood in connection with the structural details thereof. 110

Fig. 1 shows the parts in the position they assume when the current is being supplied by the predominating line by means of the conductors 33, 34 and 35. A small amount of current is supplied through the conductors 65 and 66 to excite the coil 59 and the armature 60 is thereby held in its upper position so that connection is made between the contacts 61 and 63. The circuit through the conductor 68 is broken through both branches, 115 through the conductor 70 at the contacts 62 and 64 and through the conductor 69 at the contact finger 56 and the disk 50. If for any reason the current through the predominating line fails the armature 60 will be released, connection will be made between the contacts 120 125 130

62 and 64 and the current will pass through conductor 70, contact finger 57, disk 51, conductor 72, solenoid 44 and back to the line 30. The core 45 will be drawn upward and 5 through the pitman 53 will draw the momentum member 49 toward the middle position. Just before the parts reach this middle position contact is broken at the disk 51. The momentum of the momentum member 49 10 will carry it beyond dead center and as it passes downward into the opposite extreme position the weight of the core 45 also pushes the member 49 downward. This movement is indicated in Fig. 2, the initial position being as shown in full lines and the final position being as shown in dot and dash lines. The initial position is also as indicated in Fig. 4 while the final position is as shown in Fig. 5. Figs. 4 and 5 show the manner in 15 which the eccentric 52 moves the forked end of the lever 42 and swings the shaft 14 from one extreme position to the other and breaks the lower contacts as seen in Fig. 3 and at the same time makes connections at the upper 20 contacts.

It will be noticed that the member 49 moves about sixty degrees each side of the vertical axis and as it moves farther from the vertical position the effective lever arm 25 through which the member 49 can push backward and raise the core 45 becomes less and less. And stated conversely the torque exerted by the weight of the core 45 on the member 49 becomes greater the farther the member 49 is away from the middle position. In a similar manner the eccentric 52 acts upon the forked lever 42 with an increasing ratio of leverages the farther the eccentric is moved from the middle position. This increasing leverage is particularly effective in its operation upon the spring pressed contact fingers 23 for two reasons. In the first place the force with which the springs of the fingers push back is greater the farther the contact arms move inwardly and the increasing force of the actuating weight 45 because of the increased leverage likewise increases to take care of the increasing force of the spring. Also the increased leverages in the extreme 35 positions are so marked that it is almost impossible for a force exerted at the end of the switch arms to push back through the linkages and raise the weight of the core 45. This is a desirable feature in the type of construction shown wherein the magnet is not excited after the switch has operated but the holding force is due exclusively to the weight of the core and not upon the strength of the solenoid.

Upon the restoration of the electrical supply to the lines 33, 34 and 35 the coil 59 is excited, the armature 60 is raised, contact at 40 61 and 63 made, and since the contact finger 56 is now making contact with the disk 50 45 the circuit is completed through the sole-

noid 44 and the momentum member 49 is carried back to its original extreme position. This movement operates through the linkage to open the upper contacts and closes the lower contacts of the main switch. One of the 70 advantages of the invention is due to the particular arrangement whereby the unitary magnetic device is detachably associated with a unitary switch structure. A few magnetic operating units may be carried in stock and readily assembled with a variety of different switches. The disposition of the shaft 14 and the shaft 48 parallel to the plane of the panel also contributes to the unitary feature and to the use of a plurality of switch arms and contacts. 75

While in the foregoing the invention has been described particularly in connection with a transfer switch for automatically changing a load from one source of supply to another, it is to be understood that the invention and its structural features are also adapted for use in any suitable place and more especially where a remote control switch or contactor is required. Such switches are 80 usually single throw, and with the construction of the present invention would be controlled by a manually operated, normally open, momentary contact push button switch 85 or equivalent. 90

I claim:

In a magnetic switch, a vertically disposed supporting panel, a contacting member oscillatable about a horizontal axis parallel to said panel, a momentum member also oscillatable about a horizontal axis parallel to said first named axis from one extreme position to another, a solenoid magnet having a vertically moving core adapted when the magnet is excited to move said momentum member from either extreme position toward an intermediate neutral position, means including contact discs rotatable with said momentum member for deenergizing said magnet as the momentum member travels from either extreme position toward the intermediate position, said momentum member having a relatively large mass to carry it to the other extreme position, driving connections between said momentum member and said contacting member whereby the oscillation of the former will oscillate the latter, and a stop on said core determining the extreme positions of said momentum member. 100
